United States Patent Office

Des. 226,385
Patented Feb. 27, 1973

226,385

CASSETTE TAPE RECORDER

John S. Maliskas, North Syracuse, N.Y., assignor to
General Electric Company

Original design application June 5, 1970, Ser. No. 23,335,
now Patent No. 222,360. Divided and this application
July 28, 1971, Ser. No. 176,422

Term of patent 14 years

Int. Cl. D14—01
U.S. Cl. D26—14 B

FIG.1

FIG.2

FIG.3

FIG.4

FIG.5

FIG. 1 is a top plan view of a cassette tape recorder showing my new design;

FIG. 2 is a front elevation view thereof;

FIG. 3 is a side elevation view thereof;

FIG. 4 is a rear elevation view thereof; and

FIG. 5 is a bottom elevation view thereof.

This is a division of design application Ser. No. D. 23,335, filed June 5, 1970, and now patent Ser. No. D. 222,360.

I claim:

The ornamental design for a cassette tape recorder, as shown.
